UNITED STATES PATENT OFFICE.

ANTHONY HERMAN GERARD FOKKER, OF AMSTERDAM, NETHERLANDS.

ARMOR PLATE FOR FLYING MACHINES.

Application filed June 2, 1921. Serial No. 474,466.

To all whom it may concern:

Be it known that I, ANTHONY HERMAN GERARD FOKKER, a subject of the Queen of the Netherlands, residing at Amsterdam, Netherlands, have invented a new and useful Armor Plate for Flying Machines, of which the following is a specification.

This invention relates to improvements in armor protectors for the motors and radiators and other apparatus of flying machines, as well as the persons in such machines, against rifle and machine gun fire, the object of the invention being to provide an improved armor protector which rotates with the propeller to protect the end of the machine at which the propeller is located, and to also create a blast of air which is driven into and through the radiator or cooler of the motor to enable the same to function normally in spite of the armor protecting plate, and prevent overheating of the motor cylinders.

With the above and other objects in view, the invention consists in the construction, combination and arrangement of devices hereinafter described and claimed.

In the accompanying drawings:—

Fig. 1 is a perspective view of a portion of an aeroplane provided with an armor protector constructed and arranged in accordance with my invention.

Fig. 2 is a detail rear elevation of the propeller, armor plate and fan.

Fig. 3 is a detail sectional view of the same on the plane indicated by the line 3—3 of Fig. 2.

For the purposes of this specification, the front end of an aeroplane is indicated at 1, the usual radiator cooler at 2, the propeller at 3, and the propeller shaft at 4. In accordance with my invention, I provide an armor 5 which as here shown comprises a plate 6, circular in form, and arranged on the center of the propeller and spaced from the cooler 40 or radiator, and also comprises a concavo-convex shield 7 which is arranged on the front side of the plate 6. Within the scope 45 of my invention the armor may be of any

suitable construction. I also provide a fan or blower which as here shown comprises a series of vanes or blades 8 of suitable form, which are secured on the side of the plate 6 opposed to the cooler.

The armor rotates with the propeller and the blower or fan also rotates therewith and forces strong blasts of air into and through the radiator or cooler, thereby greatly increasing the efficiency of the radiator or cooler in preventing the motor cylinders from becoming overheated. The armor also 60 serves effectually to protect the end of the machine at which it is arranged, and to also protect the occupants of the machine from rifle and machine gun fire, and also against shrapnel and shell.

My improved devices can also be attached to flying machines provided with a rear propeller, and in this case the blades or vanes of the fan are shaped and arranged in such manner as to cause them to produce a suction action.

Having thus described my invention, I claim:—

1. In a flying machine, a cooler, a propeller contiguous to and spaced from the cooler, and an armor plate and fan arranged for rotation with the propeller and also arranged contiguous to the cooler to force air against the cooler.

2. In a flying machine, a cooler, a propeller contiguous to and spaced from the cooler, an armor plate arranged for rotation with the propeller, and fan blades secured to the armor plate and arranged to force air against the cooler.

3. In a flying machine, a propeller, an armor plate arranged for rotation with the propeller, and a fan behind the armor plate and also arranged for rotation with the propeller.

In testimony whereof I affix my signature in presence of two witnesses.

ANTHONY HERMAN GERARD FOKKER.
